UNITED STATES PATENT OFFICE.

MAX M. COHN, OF SAN FRANCISCO, CALIFORNIA.

BOOKKEEPING-MACHINE.

No. 822,584.

Specification of Letters Patent.

Patented June 5, 1906.

Application filed July 3, 1905. Serial No. 268,227.

To all whom it may concern:

Be it known that I, MAX M. COHN, a citizen of the United States, residing in the city and county of San Francisco and State of California, have invented new and useful Improvements in Bookkeeping - Machines, of which the following is a specification.

My invention relates to a machine for book-keeping or posting and to a system of ac-
counting, and especially to a machine for and a system of posting items to a ledger-account and keeping the ledger accurately balanced at all times.

Under present methods an immense amount of labor is entailed on the office force of large business houses to keep the various items of sales and cash receipts properly posted to the various accounts, and a still greater effort is necessary at the end of each month to get a correct balance, commonly known as the "trial balance."

The object of the present invention is to provide a time and labor saving means which does away with copying or writing by hand the amount of sales, credit memoranda, and cash items into a ledger-account, and to provide a means for keeping the books always accurately balanced.

The invention consists of the parts and the construction and combination of parts, as hereinafter more fully described and claimed, having reference to the accompanying drawings, in which—

Figure 1 is a side elevation of my apparatus. Fig. 2 is a front elevation of same. Fig. 3 is a sectional view of the sprocket. Fig. 4 is a sectional view of three bars, showing the overlapping of the ledger-sheets. Fig. 5 is a perspective view of a movable bar. Fig. 6 is a perspective view of a removable bar or clamping-bar. Fig. 7 shows a modification of that shown in Fig. 1. Fig. 8 is a view looking from the left of the drum shown in Fig. 7. Fig. 9 represents the sheet of a loose-leaf ledger. Fig. 10 represents the sheet of the guide-strip.

In Fig. 1, which illustrates the form of machine preferred where there are several hundred accounts to be changed, A is a frame of suitable size and design in which are suitably journaled a plurality of pairs of sprocket-wheels 2. The sprockets are shown as journaled on arbors, leaving the space between the sprockets on the two sides within the frame entirely open, so as not to interfere with the ledger-sheets, which are adapted to

be carried on suitable conveying means passing over the sprockets.

The conveying means for the ledger-sheets, bills, statements, or the like to be printed on 60 consists of alternating long and short bars or slats 3 4. The slats are perforated near their ends and are connected in endless-carrier fashion by means of the endless wire cables 5, passing through the perforations in the bars. 65

A bar or slat 6 is made fast to the cables 5 and forms a starting-point on the carrier, and all the other bars or slats 3 4 are slidable on the cables in relation to the bar or slat 6. When all the bars 3 4 are pushed around and 70 pressed against one side of the bar 6 and are in close contact with each other, there will be a space of one or two inches, more or less, between the other side of the bar 6 and the last of the series of bars 3 or 4. This space (rep- 75 resented at 7) is for the purpose of allowing independent movement of any of the movable bars 3 4 to enable the sheets to be put into or taken out of the machine, as will be described shortly. 80

The teeth of the sprockets 2 are peculiar, in that they are partly cut away to form outside flanges 8, against which flanges the shorter bars or slats 4 abut and between which flanges or teeth the long bars or slats 3 85 engage. The purpose of cutting the teeth in this fashion is to accommodate the bars, which must lie side by side, and to provide suitable guide means against any possible longitudinal movement of these carrier bars 90 or slats.

It will be observed that by using long and short bars or slats 3 4 and cutting the teeth on the sprockets in the manner shown the bars can lie close to one another, working with 95 the utmost smoothness, and at the same time the abutment of the teeth or so-called "flanges" 8 against the ends of the short bars 4 will operate to maintain the bars in the most perfect relation with the printing at- 100 tachment of an adding-machine, as C, with which my machine is adapted to be used. The slats of the carrier are supported between the sprockets on suitable guides a' on the frame A. Each side of each bar is cut 105 out, as at 8', between the ends of the bar, equal approximately to the length and thickness of the sheet which is to be posted onto. These recesses or depressions on the sides of a bar correspond substantially in length to the 110 length of the sheet to be inserted, and their object is to allow the bars always to be shoved

22
up snug against one another irrespective of the number of sheets that may be on the carrier. If some such means as the recesses 8' were not provided, the distance of any particular movable bar from the bar 6 would vary according to the number of sheets of paper included between said movable bar and the fixed bar. Thus if there were two hundred sheets of paper inserted between the fixed bar and the succeeding two hundred movable bars or slats, and if the aggregated thickness of these sheets amounted to one inch, then the two hundredth movable bar or slat would be one inch farther removed from the fixed bar or slat than if there were no sheets between said two hundredth bar and the fixed bar. With my arrangement, however, with all the bars shoved up against one another and against the fixed bar the distance of the said two hundredth bar from the fixed bar remains always the same.

10 The bars 3 4 are all of uniform width—say about a quarter of an inch—and equal to the distance between the lines of a sheet to be posted to. The various bars or slats may be 15 of any suitable material, either wood or metal or celluloid or the like, and preferably provided with a suitable resilient surface of rubber or other material suitable for type-face to impinge upon.

10 3 and 10 represent two metal strips or guides, which are fixed to the frame A and extend all around the carrier and project over and cover the opposite ends of the bars. 20 At some suitable point between the different pairs of sprockets, and preferably at the front of the machine, as shown, these guides 9 10 are cut away to provide a suitable opening for the insertion of the sheets, which latter at 25 all points in their travel except across this opening are adapted to be engaged at their ends by the guides 9 10 and held in place thereby.

20 B represents the sheet of a loose-leaf ledger, such as in common use, and having lines spaced from each other in exact correspondence with the width of the bars 3 4. If desired, the sheet B may be creased on these lines so as to be easily folded flat over any 30 movable bar and be clamped between the two adjacent bars when the three bars are shoved up into contact with each other. By having a sheet creased, as at b, the insertion of the sheets over and between the bars 35 is materially facilitated, besides assisting in securing uniformity in the arrangement of the matter and figures designed to be type-written on the sheet.

30 To insert the sheets into the machine, the carrier is turned to bring the fixed bar 6 into the open space 7 between the ends of the guides 9 10. The series of movable bars 3 4 having been suitably separated from one side of the fixed bar 6, as indicated by the 45 opening 7, the bar 3 or 4 on the other side of

this opening is moved part way across the opening, so that a folded sheet B can be made to straddle this bar. This bar with its sheet is moved up against the bar 6 and the carrier turned by hand to move the ends of the bar and the outer edges of the sheet under the spring ends of the guides 9 10. A succeeding movable bar is then advanced into the open space and a sheet folded over it and moved up against the first bar and its sheet and under the guides 9 10. Thus sheet after sheet is folded or bent and laid over a bar, and the bars move up one behind the other until all the sheets representing all the accounts in the ledger to be 50 changed at that time are inserted. The enclosed space 7 then remaining between the bars is closed by means of a series of removable bars 12, which have the notches 13, allowing these blank spacer-bars to be hooked 55 over the cables 5. If the space 7 is two inches in width, and the uniform width of all the bars is a quarter of an inch, there would be eight of these spacer-bars inserted into the space 7, serving to keep all the bars 60 pressed tightly against each other and against the fixed bar 6.

50 The guide-straps 9 10 are so arranged that they just overlap the narrow exposed strips of the sheets and prevent the sheets falling 65 out from between the clamp-bars 3 4 and also serve the same function in regard to the spacing-bars 12. When all the sheets are clamped in the frame, there is only an amount of each sheet showing that corresponds to 70 the width of a clamp-bar and to the space between the guides 9 10. Having thus provided suitable means for holding a number of sheets and for simultaneously exposing a limited portion only of each sheet, I am able 75 by means of suitable connections with an adding-machine to post directly and mechanically to each sheet the entry which heretofore has generally been carried forward into the ledger by laboriously writing 80 in by hand.

70 In the present instance and for convenience of illustration I have shown my apparatus used in conjunction with a Burroughs adding-machine; but it is obvious that other 85 machines are applicable in the same combination.

75 C represents an adding-machine having the usual type mechanism c, which is adapted to be projected outward on the actuation of the lever 14 to the left to print upon a strip of paper held in suitable relation to the type. I simply remove the paper-holding roller and carriage of the ordinary Burroughs machine, and instead of printing onto a separate strip 120 of paper I print directly onto the sheets which are carried by the clamp-bars 3 4.

80 The adding-machine is mounted on a carriage 15, which is provided with rollers 16, running in grooves which extend transversely 125 130

- of the base *a* of the frame *A*. This base is enough wider than the machine for holding the sheets to permit the adding-machine to be moved clear to one side, so as to expose all the printed matter on the exposed portion of the sheets on the carrier and allow the sheets to be easily placed on or taken off of the carrier. A feather-shaft 17 is supported on the base in suitable relation to the carrier mechanism and to the adding-machine and carries a ratchet 18, which is slideable thereon and turnable therewith. This ratchet is supported in the crotch of a forked lever 19, which is fulcrumed on the shaft 17 and slideable on the shaft, but turnable independently of the shaft. This lever 19 carries a pawl 20, adapted to engage with the ratchet to turn it and the shaft 17 when the lever 19 is moved in one direction and to ride free over the ratchet when the lever swings in the other direction. This lever 19 is made to move back and forth with the adding-machine *C* and to have its outer end always disposed in the path of a cam 21 on the operating-lever 14 of the adding-machine. This movement of the lever with the adding-machine is insured by means of a curved bracket 22, secured to the adding-machine and embracing the lever without interfering with its oscillating movement.
- One end of the shaft 17, and preferably that end toward which the adding-machine is moved when it is desired to get at the carrier, is provided with a pinion 23, engaging a large gear 24 on the shaft of one of the sprockets 2. Hence it will be observed that whenever the lever 14 on the adding-machine is thrown forward to cause the cam 21 to rock the lever 19 the ratchet 18 will move one step, turning the shaft 17 and operating through the gears 23 24 to advance the carrier one bar-space. It is understood that the parts are so arranged and assembled that a clamp-bar will always be brought at each actuation of the lever 19 into exact and proper relation with the type-face of the printing mechanism *c*.
- In making an entry, assuming the adding-machine to be moved so as to bring the type-face opposite the proper place where it is desired to print upon the sheets, the appropriate keys 25 on the adding-machine are depressed. Pulling the lever 14 to the left operates in the usual manner, not necessary here to be shown or described, to throw the type outward and make the proper imprint on the particular sheet on the particular bar which at that moment happens to be in the path of the type. Throwing the lever 14 back to normal position, which is the position indicated in Fig. 1, the printing devices are retracted, which will permit the carrier to move. Before, however, depressing the keys 25 for the next entry the lever 14 is rocked forward, or to the right, to cause the cam 21 to depress the lever 19 and advance
- the carrier one bar-space and bring the next bar with its sheet into the path of the printing devices, whereupon the next entry may be made by depressing the appropriate keys and rocking the lever 14 to the left, and so on through the whole series.
- In order to afford some sort of a guide for the operator that he may know just which particular sheet or bar is being printed on at a particular time, I have numbered the bars in a certain systematic manner which will permit him, by looking at a slot 26 in a guide-strip 9, to determine just which bar is in the path of the printing devices. For this purpose all the movable bars at one end are numbered consecutively from one side of the fixed bar 6 around toward the other side of this fixed bar. These numbers appear through the slot 26. The slot 26 is disposed at a known distance from the line of type, which may be said to be six inches, measured around on the curve of the carrier. Hence if all the clamp-bars are one-quarter of an inch thick there would intervene twenty-four bars between the slot 26 and the printing devices. Consequently the twenty-fourth bar from this slot would always be the bar which carries the sheet immediately opposite the printing devices. Starting with number "1," showing through the slot 26, the twenty-fourth bar from this slot, measured in the correct direction, would be numbered "1." These latter numbers would be placed on the ends of the bars opposite to or to the right of those numbers which appear in the slots 26, and the said latter numbers would run consecutively, so that whatever number appears in slot 26, it would be known that a bar bearing exactly the same number is directly opposite to the printing devices.
- In the practical application of my invention I proceed as follows: The various entries are listed on a regular adding-machine in the usual fashion on narrow slips of paper, such as shown at *D*. There is a list for sales, a list for cash credits, a list for credit memoranda, a list for journal entries, and a list for any kind of entries that are to be transferred or posted into the ledger or other permanent record. If desired, these sales may be made on strips of different colored paper to assist in the ready recognition of the several entries. These lists are verified and must be absolutely correct. They should be made on strips that are consecutively numbered correspondingly with the numbers on the bars of the clamping-machine. If desired, the numbers can be placed on the slips with the aid of a numbering-machine. After these slips are prepared the ledger sheets or cards that are to be posted are taken from their binders or files and dated and numbered with a combined dating and numbering machine, which also prints the classes of entries, (as *M*. for merchandise, *C*. for cash, &c.) The number on these ledger-sheets correspond

with the numbers appearing on the strip D opposite the amount to be posted to that particular account.

When the ledger-sheets have been dated and numbered, they are placed in numerical order in the bookkeeping-machine, and the prepared list is also placed in the machine with one end clamped between two of the bars 3 or 4, and under the guide-strip 9 and with number "1" on the list corresponding with number "1" at the left of the machine viewable through the slot 26. The ledger-sheets, however, are placed in the machine in consecutive order corresponding with the numbers on the right of the machine. While the numbers on the two ends of the bars run the same way around the carrier, the two numbers on the opposite ends of any one bar will differ from each other, as we have seen, by just the numbers of bars that there are between slots 26 and the printing device.

The list D when inserted into the machine travels under the guide 9, and the number of spaces on the list so correspond with the slats on the carrier that the movement of the carrier each time it is advanced to bring a new ledger-sheet in front of the printing-wheel, a number corresponding to the number of this sheet appears through the slot 26. The slot 26 is also of such shape and size that the amount which is to be transferred onto the ledger-sheet appears through this slot. All that is then necessary for the operator to do is to depress the proper keys and pull the lever, which will print the amount to be posted on the proper sheet. Pushing the lever in the opposite direction advances the carrier and the guide-slip D, bringing the next sheet into correct position with the printing-wheel of the adding-machine and exposing the succeeding number and amount in the slot 26, which is in plain view of the operator. The same operation is repeated until the entire list is posted and the total is shown in the slot. The total-key is then depressed on the adding-machine and the amount printed on a total or balance sheet carried by the carrier and which may be kept in the back of the ledger. After all the sheets have been properly posted the adding-machine is moved to one side and the bar 6 brought into the opening space 7 between the ends of the guides 9 10. The spacer-bars are removed and the sheets are then taken out one at a time, beginning with the sheet which was inserted last into the machine. This process of taking out the sheets brings the slats 3 4 into their original position relative to the bar 6 and with the opening 7 on the same side of the bar 6, so that the movable bar which is just across this opening nearest to bar 6 will be numbered "1" at its right end.

Where a great many accounts are handled, it is preferable to group them, using a total or balance sheet after each group, so that a

separate balance or total may be kept for each group. In case accounts are kept in alphabetical order a total or balance sheet may be used after each letter and proved up separately in the manner above described. 70

Where accounts are kept in geographical arrangement, a total or balance sheet may be used after each town, country, or State, as may be required.

This system insures absolute accuracy, 75 greatly reduces the amount of labor in an office, and allows the office-work to be kept up to date.

Where the ledger-sheets are ruled into separate entry-columns, (indicated at 27,) the base a may have a series of corresponding graduations 28, and the adding-machine may be provided with a pointer 29. The pointer 29 and the graduations 28 would serve to indicate to the operator when he has moved 85 his adding-machine into proper juxtaposition with a particular column in which the entries are to be made on the ledger-sheet.

In my method of bookkeeping the accounts can be provided in sections. A trial 90 balance is automatically secured at the end of each day. Under present methods there is always a doubt as to the source of an error, there being a chance of an error in the original entry, as well as a chance for an error in 95 transferring the original entry to the ledger. This doubt is now eliminated.

This system can be used in all operations requiring the transfer of original entries to permanent or classified records, embraces all 100 posting, such as charges, credit memoranda, cash entries, stock-records, and the like.

The machine can also be used for making out bills and statements.

In Fig. 7 I have shown a modification of 105 my invention which is adapted more particularly for use where there are only a limited number of changes each day to be made. In this case I use the same idea of an endless carrier with clamp-bars, in combination with 110 an adding-machine; but instead of a flexible carrier passing over sprocket-wheels I employ a cylinder, as A', mounted to revolve upon a suitable support and arranged in proper relation to a shiftable adding-machine C'.

The cylinder is composed of two heads having annular flanges 30 on their inner sides, on which the clamp-bars 31 are slidable in relation to a bar 6', which is made fast to 120 the heads of the cylinder. The sheets are clamped between the bars in the same manner as described in connection with Fig. 1, and they and the bars are held into position by means of the end guides 9' 10', a guide 10' 125 being fixed to and movable with the cylinder, but the guide 9', which has the slot 26', being stationary and having a suitable support independent of the cylinder. A step-by-step movement is given to the cylinder by 130

a mechanism similar to that described in connection with Fig. 1.

It is possible that various modifications in my invention may be made without departing from the principle therefor, and I do not wish to be understood as limiting myself to the specific construction as herein shown and described.

Having thus described my invention, what I claim, and desire to secure by Letters Patent, is—

1. The combination with the printing device of an adding-machine, of carrier means for independently holding and exposing a plurality of detached sheets in operative relation to said printing device, one of said parts movable in relation to the other, and said parts arranged and operable to permit the imprinting of the sheets while on the carrier means.

2. In apparatus of the character described, the combination with the printing device of an adding-machine, of a holder for holding a series of detached sheets in operative relation to the printing device on the adding-machine to permit the imprinting on said sheets without removing the sheets from the holder, and means for presenting said sheets successively to the printing device.

3. In apparatus of the character described, the combination with the printing device of an adding-machine, of a movable holder for holding a series of detached sheets in operative relation to said printing device, said holder arranged to present the sheets to the printing device to permit their imprinting without removal from the holder, and connections between the holder and adding-machine to operate the holder coördinately with the printing device.

4. The combination with a suitable printing device of an adding-machine of an endless carrier having means for supporting a plurality of sheets, and for giving motion to the carrier to bring said sheets successively into operative relation with said type-writing mechanism, said carrier arranged to present the sheets directly to the type-writing mechanism to permit their imprinting without disturbing their position on the carrier.

5. The combination with a printing device of an adding-machine, of a slotted carrier having suitable clamp means to hold a plurality of sheets, and connections between the type-writing mechanism and the carrier to operate the carrier coördinately with the type-writing mechanism, said carrier arranged to present the sheets directly to the type-writing mechanism to permit their imprinting without disturbing their position on the carrier.

6. In apparatus of the character described, a slotted endless carrier having means for holding a folded sheet of paper with the ends of the sheet projecting within the carrier, and

means for printing on the folded part of a sheet while the latter remains on the carrier.

7. In apparatus of the character described, a slotted endless carrier having means for holding a folded sheet of paper with the ends of the sheet projecting within the carrier, and with the fold of the sheet exposed, means for giving the carrier a step-by-step movement, and means for printing on the exposed part of the sheet while it is still on the carrier. 75

8. In apparatus of the character described, the combination of a slatted endless carrier, said carrier provided with means for holding a folded sheet of paper with its ends between the slats and projecting into the carrier, said 80 slats forming supports for the folds of the sheets.

9. In apparatus of the character described, an endless carrier having a series of movable slats between which the folded sheets of paper are adapted to be clamped, and means coöperating with said slats to hold the sheets in position. 85

10. In apparatus of the character described, an endless carrier having a series of 90 movable slats between which the folded sheets of paper are adapted to be clamped, means coöperating with said slats to hold the sheets in position, and printing mechanism associated with said carrier.

11. In apparatus of the character described, a paper-carrier including a plurality of bars over which sheets are adapted to be bent, means for holding the sheets between the bars, means for giving the holder a step-by-step movement, and printing mechanism 100 associated with the holder.

12. In apparatus of the character described, the combination of an endless carrier having a fixed bar and a series of other 105 bars movable in relation to said fixed bar, said several movable bars adapted to hold each a separate sheet of paper, a printing attachment, and means for operating said carrier synchronously with the operation of the 110 printing attachment to present the sheets carried by said bars successively to said printing attachment.

13. The combination with the printing attachment of an adding-machine of an endless 115 carrier having means for holding a plurality of detached sheets, means for operating said carrier to bring the sheets successively into operative relation with the printing attachment on the adding-machine, a movable carriage for the latter, said carrier arranged to present the sheets to the printing attachment to permit their imprinting without disturbing their position on the carrier. 120

14. In apparatus of the character described, the combination with the printing device and the operating-crank of an adding-machine, of a carrier having means for holding a plurality of sheets, connections between said crank and said carrier to operate the 130

latter, said carrier arranged to present the sheets to the printing attachment to permit their imprinting without disturbing their position on the carrier.

15. In apparatus of the character described, the combination with the printing device and the operating-crank of an adding-machine, of a carrier having means for holding a plurality of sheets, and connections between said crank and said carrier to operate the latter, said last-named means including a pawl-and-ratchet mechanism, a lever to operate the ratchet and a cam on said crank to engage said lever.

16. In apparatus of the character described, an endless carrier having a plurality of transversely-movable slat members, means permitting the emplacement of sheets of paper over and between said slat members, and means for holding said sheets in position.

17. In apparatus of the character described, an endless carrier having a plurality of transversely-movable slat members, means permitting the emplacement of sheets of paper over and between said slat members, means for holding said sheets in position, and a printing device associated with said carrier.

18. In apparatus of the character described, an endless carrier having a plurality of transversely-movable slat members, means permitting the emplacement of sheets of paper over and between said slat members, a means for holding said sheets in position, a printing device associated with said carrier, a crank to operate the printing device, and connections between the crank and carrier to operate the latter.

19. In a bookkeeping-machine, the combination of a carrier having a series of movable slats over and between which sheets of paper are adapted to be bent and held, means for holding the bended sheets on the slats, and means for moving the carrier.

20. In a bookkeeping-machine, the combination of an endless carrier having a series of movable slats over and between which the sheets of paper are adapted to be bent and held, means for holding the bended sheets on the slats, means for moving the carrier and mechanism for printing upon said bended sheets while on the carrier.

21. In a bookkeeping-machine, the combination of a frame, sprockets journaled therein, a carrier comprising a series of flexibly-conjoined independently-adjustable slats passing around said sprockets, each slat adapted to have a sheet of paper or the like bent over it and to clamp the sheet between it and the two contiguous slats.

22. In a bookkeeping-machine, the combination of a frame, sprockets journaled therein, a carrier comprising a series of flexibly-conjoined independently-adjustable slats passing around said sprockets, each slat

adapted to have a sheet of paper or the like bent over it and to clamp the sheet between it and the two contiguous slats, and means for printing on the sheets carried by the slats.

23. In a bookkeeping-machine the combination of a frame, sprockets journaled therein, a carrier comprising a series of flexibly-conjoined independently-adjustable slats passing around said sprockets, each slat adapted to have a sheet of paper or the like bent over it and to clamp the sheet between it and the two contiguous slats, means for printing on the sheets carried by the slats, and means for moving the carrier coördinately with the operation of the printing mechanism.

24. In a bookkeeping-machine the combination of a frame, sprockets journaled therein, a carrier comprising a series of flexibly-conjoined independently-adjustable slats passing around said sprockets, each slat adapted to have a sheet of paper or the like bent over it and to clamp the sheet between it and the two contiguous slats, guide-strips extending nearly around the carrier and outside of and contiguous to the slats and operating to prevent the sheets falling out from between the slats.

25. In a bookkeeping-machine the combination of a frame, sprockets journaled therein, a carrier comprising a series of flexibly-conjoined independently-adjustable slats passing around said sprockets, each slat adapted to have a sheet of paper or the like bent over it and to clamp the sheet between it and the two contiguous slats, guide-strips extending nearly around the carrier and outside of and contiguous to the slats and operating to prevent the sheets falling out from between the slats, and a printing attachment in conjunction with said bookkeeping-machine.

26. In a bookkeeping-machine the combination of a frame, sprockets journaled therein, a carrier comprising a series of flexibly-conjoined independently-adjustable slats passing around said sprockets, each slat adapted to have a sheet of paper or the like bent over it and to clamp the sheet between it and the two contiguous slats, guide-strips extending nearly around the carrier and outside of and contiguous to the slats and operating to prevent the sheet falling out from between the slats, a printing attachment in conjunction with said bookkeeping-machine, and indicator means on the slats representing the particular slat which may be opposite in the printing attachment.

27. A bookkeeping-machine, the combination of a frame, sprockets carried thereby, an endless carrier passing over said sprockets and comprising a series of flexibly-conjoined, independently-adjustable, alternately-arranged, long and short slats, said long slats fitting between the teeth of the sprockets and

said teeth forming end abutments for the short slats.

28. In a bookkeeping system, an endless carrier having a series of flexibly-conjoined, independently-adjustable slats over and between which sheets of paper are adapted to be bent and held, guides extending around the carrier and partly over it, and coöperating with the slats to hold the sheets in position.

29. In a bookkeeping system, an endless carrier having a series of flexibly-conjoined, independently-adjustable slats over and between which sheets of paper are adapted to be bent and held, guides extending around the carrier and partly over it, and coöperating with the slats to hold the sheets in position, and a printing device associated with the carrier.

30. In a bookkeeping system, an endless carrier having a series of flexibly-conjoined, independently-adjustable slats over and between which sheets of paper are adapted to be bent and held, guides extending around the carrier and partly over it and coöperating with the slats to hold the sheets in position, and a printing device associated with the carrier, said slats having indicating means coöperating with means provided by one of said guides to indicate to the operator the particular slat opposed to said printing device.

31. In a bookkeeping system, an endless carrier having a series of flexibly-conjoined, independently-adjustable slats over and between which sheets of paper are adapted to be bent and held, guides extending around the carrier and partly over it and coöperating with the slats to hold the sheets in position, a printing device associated with the carrier, said slats having indicating means coöperating with means provided by one of said guides to indicate to the operator the particular slat opposed to said printing device, and a flexible strip or tape carried by the carrier and having notation corresponding to said indicating means on the slats.

32. In a bookkeeping system, an endless carrier having a series of flexibly-conjoined, independently-adjustable slats over and between which sheets of paper are adapted to be bent and held, guides extending around the carrier and partly over it and coöperating with the slats to hold the sheets in position, and a printing device associated with the carrier, said slats having indicating means coöperating with means provided by one of said guides to indicate to the operator the particular slat opposed to said printing device, said indicating means including consecutive numbering on each end of said slats, and a flexible strip or tape carried by the carrier and having consecutive numbering corresponding to the numbering on the slats.

33. In a bookkeeping-machine, the combi-

nation of an endless carrier having a series of 65 flexibly-conjoined movable slats over certain of which slats sheets of paper are adapted to be bent and the ends to be received between adjacent slats, and means coöperating with said slats to hold the sheets in position.

34. In a bookkeeping-machine, the combination of an endless carrier having a series of 70 flexibly-conjoined movable slats over certain of which slats sheets of paper are adapted to be bent and the ends to be received between 75 adjacent slats, means coöperating with said slats to hold the sheets in position, and printing means associated with said carrier means.

35. In a bookkeeping-machine, the combination of an endless carrier having a series of 80 flexibly-conjoined movable slats over certain of which sheets of paper are adapted to be bent and the ends to be received between adjacent slats, means coöperating with said slats to hold the sheets in position, said last- 85 named means including guide-strips partly surrounding the carrier.

36. In a bookkeeping-machine, the combination of an endless carrier having a series of 90 flexibly-conjoined movable slats over certain of which sheets of paper are adapted to be bent and the ends to be received between adjacent slats, means coöperating with said slats to hold the sheets in position, said last- 95 named means including guide-strips partly surrounding the carrier, operating means as- 100 sociated with the carrier and indicator means on the slats to indicate to the operator the particular slat which may be in operative position with the printing means.

37. In a bookkeeping-machine, the combination of an endless carrier having a series of 105 flexibly-conjoined movable slats over certain of which sheets of paper are adapted to be bent and the ends to be received between adjacent slats, means coöperating with said slats to hold the sheets in position, said last- 110 named means including guide-strips partly surrounding the carrier, operating means as- 115 sociated with the carrier and indicator means on the slats to indicate to the operator the particular slat which may be in operative position with the printing means, said indicator means including related notation on opposite ends of the slats, and guide means on one of 120 said guide-strips relative to the notation on one end of said slats.

38. In a bookkeeping system, the combination of an endless carrier having a series of 125 flexibly-conjoined movable slats over certain of which sheets of paper are adapted to be bent and the ends to be received between adjacent slats, means coöperating with said slats to hold the sheets in position, said last- 130 named means including guide-strips partly surrounding the carrier, operating means as- 135 sociated with the carrier and indicator means on the slats to indicate to the operator the

particular slat which may be in operative position with the printing means, said indicator means including related notation on opposite ends of the slats, guide means on one of said 5 guide-strips relative to the notation on one end of said slats, and a flexible strip or tape carried by the carrier and having notation corresponding to the last-mentioned notation on the slats.

39. In a bookkeeping system, a machine having means for holding a series of sheets of paper and for exposing a limited portion only of each sheet, a type-writing machine juxtaposed to the sheet-holding means and suitably arranged to print on said sheets, means 10 for operating the sheet-holding means coördinately with operation of the type-writing machine to bring the sheets successively into operative relation with the type-writing 15 means.

40. In a bookkeeping system, a machine having means for holding a series of sheets of paper and for exposing a limited portion only of each sheet, a type-writing machine juxtaposed to the sheet-holding means and suitably arranged to print on said sheets, means 20 for operating the sheet-holding means coördinately with operation of the type-writing machine to bring the sheets successively into operative 25 relation with the type-writing means, and means to indicate to the operator the particular sheet which may happen to be in such operative position.

41. In a bookkeeping-machine, the combination of an endless carrier having a series of 35 flexibly-conjoined, independently-adjustable slats, guide-strips embracing the carrier and out of contact with or in very light contact with the slats, said slats having a double series of related notation, and one of said guide-strips having a slot through which one series 40 of said notation is viewable.

42. In a bookkeeping system, the combination of a frame, an endless carrier thereon 45 having a series of flexibly-conjoined, independently-adjustable slats, a printing device mounted for reciprocation on said frame and transverse to the direction of movement of the carrier, and connections between the 50 printing device and the carrier to move the

latter coördinately with the operation of the printing device.

43. In a bookkeeping system, the combination of a frame, an endless carrier comprising flexibly-conjoined, independently-adjustable slats, an adding-machine or equivalent printing device mounted for reciprocation on said frame transverse to the direction of movement of the carrier, an operating-crank on the adding or printing machine, and means connected with the carrier and operated by the crank to move the carrier step by step.

44. In a bookkeeping system, the combination of a frame, an endless carrier comprising flexibly-conjoined, independently-adjustable slats, an adding-machine or equivalent printing device mounted for reciprocation on said frame transverse to the direction of movement of the carrier, an operating-crank on the adding or printing machine, and means connected with the carrier and operated by the crank to move the carrier step by step, said last-named means including a feather-shaft, a ratchet slidable on and turnable with the shaft, a lever fulcrumed on the shaft and slidable with the ratchet, a pawl carried by the lever, and a support on the adding-machine for the lever.

45. In a bookkeeping system, the combination of a frame, an endless carrier comprising flexibly-conjoined, independently-adjustable slats, an adding-machine or equivalent printing device mounted for reciprocation on said frame transverse to the direction 80 of movement of the carrier, an operating-crank on the adding or printing machine, means connected with the carrier and operated by the crank to move the carrier step by step, and indicator means to indicate to the operator which slat is opposite the imprinting mechanism, said indicator means including a flexible consecutively-numbered strip D.

In testimony whereof I have hereunto set my hand in presence of two subscribing witnesses.

MAX M. COHN.
